UNITED STATES PATENT OFFICE.

LEONARD A. YOUNG, OF HIGHLAND PARK, MICHIGAN.

SEAT-BACK SPRING.

1,192,363.

Specification of Letters Patent. Patented July 25, 1916.

Application filed January 8, 1916. Serial No. 70,893.

To all whom it may concern:

Be it known that I, LEONARD A. YOUNG, a citizen of the United States, residing at Highland Park, county of Wayne, State of Michigan, have invented a certain new and useful Improvement in Seat-Back Springs, and declare the following to be a full, clear, and exact description of the same, such as will enable others skilled in the art to which it pertains to make and use the same, reference being had to the accompanying drawings, which form a part of this specification.

This invention relates to seat back springs and comprises an improved seat back spring in which the arches are constructed of wavy wire and are connected in pairs so that one arch of a pair is arranged to help resist stresses put upon the other arch of the pair.

Another feature of construction is the mounting of the zig-zag or wavy wire arches in such a way that they can be subjected to unusual stresses without liability of being broken.

These features will more fully appear in the detailed description following.

In the drawings,—Figure 1 is a front elevation of the seat back spring with some of the parts omitted to show the structure to the rear thereof. Fig. 2 is a vertical section showing in dotted lines how one arch of a pair assists the other arch. Fig. 3 is a detail of a pair of the arches. Fig. 4 is a detail showing the action at the top of the seat back spring. Fig. 5 is a detail showing how the top of the seat back spring can be subjected to unusual stresses without injury to the arches.

In the construction of seat back springs, especially those employing wavy wire or zig-zag wire arches, it has been found that the arches frequently break, leaving sharp ends which often protrude through the upholstery and injure it. This is due to the fact that no provision is made to protect the arches from unusual stresses. It is the object of the construction of this seat back spring to obviate this trouble.

a indicates a base frame provided with suitable cross bars *b*, here shown as channel bars, to carry the helical springs *c*. Two horizontal rows of springs are shown although obviously this arrangement can be varied without affecting the gist of the invention. The front structure of the seat

back spring comprises a plurality of elongated heart-shape wire units *d*, each comprising a single wire, one end of which is clamped into the channel bar at the bottom 60 of the base frame *a*, which then runs upwardly over the helical springs and is twice looped at the top, the connecting run of wire between the two loops being looped over the top coil of the adjacent helical 65 spring to connect the unit to the helical springs. The single wire then continues back down over the helical springs and its other end is clamped into the bottom channel bar of the base frame *a*. The upright 70 runs of wire of each unit are clamped to the top coil of each helical spring *c* at the sides by small clips.

Each wire unit is surmounted by a pair of wavy wire or zig-zag arches *g* formed in 75 one complete arch unit by a connecting run of wire *e* at the forward end of each pair of arches (see Fig. 3). The purpose of making two arches of one integral piece of wire is the lowering of the manufacturing cost 80 and the further important reason that one arch of a pair assists its companion arch in, resisting stresses brought upon the companion arch. This is shown in Fig. 2. If one arch is subjected to a heavy stress so as to 85 depress it as shown in the lower dotted lines of Fig. 2, it will be found the companion arch will depress as shown in the upper dotted lines of this figure. Hence it is evident that the companion arch assists the first 90 mentioned arch in resisting this stress and offers a yieldable resistance because of its elastic nature. The strain on the arch subjected to the stress is transmitted through the connecting run of wire *e* as a torsional 95 strain, and this torsional strain on the connecting run *e* is communicated to the companion arch which distorts as shown in Fig. 2 in its efforts to resist this strain. This communication of strains from one 100 arch to another would not be possible were it not for the fact that the connecting runs of wire *e* are hinged to the front structure by reason of the clips *f* being loosely clamped over the tops of the loops of the 105 wire units *d* and the top front border wire of the front structure of the seat back spring. Hence the arches are free to pivot on their front ends as distinguished from the action heretofore incident to spring 110 structures of this type, for it has been customary to either rigidly connect the front

ends of the arches to the front structure or else to continue the wire which forms the arches down over the helical springs to form part of the front structure. In the last 5 mentioned forms of construction if the wire arches are subjected to such strains as follow such distortion as shown in Figs. 2 and 5, they would very soon snap. Fig. 5 shows how the seat back spring may be subjected 10 to a very heavy stress and yet how the arches will accommodate themselves to the distortion with very little strain upon them by reason of the pivoting arrangement at the front of the arches. It is also advantageous 15 to pivot the rear ends of the arches by loose clips *h* which secure the rear ends of the arch wires to the top border wire *i* of the base frame *a*.

What I claim is:

- 20 1. In a seat back spring, the combination of a base frame, a front structure, a plurality of helical springs connecting the front structure and the base frame, the said front structure including wire units having loops 25 at the top, a plurality of zig-zag wire arches connecting the said loops of the wire units with the top of the base frame, and clips for hingedly connecting the forward ends of the zig-zag wire arches with the tops of 30 said loops.
2. In a seat back spring, the combination of a base frame, a front structure including wire units having loops at the tops, helical springs connecting the front structure and the base frame, a plurality of zig-zag wire arches connecting the tops of said loops and the top of the base frame, and said front 35 structure including also a border wire running along the tops of said loops of the wire 40 units, the said forward ends of the said arches being connected with the border wire and the tops of the loops of the wire units in hinging relation.

3. In a seat back spring, the combination of a base frame, a front structure including 45 a plurality of wire units having loops at their tops, helical springs spacing the front structure and the base frame, a plurality of zig-zag wire arches connecting the tops of said loops and the top of the base frame, 50 said front structure including also a border wire running along the tops of said loops, and clips bound around the forward ends of the said arches, the border wire and the tops of the loops, and arranged to hold the forward ends of the wire arches in hinging relation.

4. In a seat back spring, the combination of a base frame, a front structure including a plurality of wire units, each having two 60 loops at its top, a plurality of spring arches connecting the tops of the said loops with the top of the base frame, the said arches being arranged in pairs, each pair being constructed of one piece of wire having a 65 connecting run at the forward end, and means for hingedly connecting each pair of arches with each pair of loops of a wire unit.

5. In a seat back spring, the combination 70 of a base frame, a front structure, a plurality of helical springs connecting the front structure and the base frame, a plurality of arch springs disposed in substantially vertical planes and in parallel relation and 75 formed in pairs, each member of a pair being integrally connected at the front by connecting runs of wire substantially perpendicular to the arches, and loose clips for engaging about the connecting runs of wire 80 and parts of the front structure for hinging the arch springs thereto.

In testimony whereof, I sign this specification.

LEONARD A. YOUNG.
